DESIGN FOR A COMBINED SIGNAL LIGHT AND REAR VIEW MIRROR

Paul A. Chambers, Santa Monica, Calif., assignor
of one-half to Loyal E. Harris, Santa Monica,
Calif.

Application March 7, 1946, Serial No. 127,192

Term of patent 3½ years

(Cl. D48—32)

To all whom it may concern:

Be it known that I, Paul A. Chambers, a citizen of the United States, residing in Santa Monica, in the county of Los Angeles and State of California, have invented a new, original, and ornamental Design for a Combined Signal Light and Rear View Mirror, of which the following is a specification, reference being had to the accompanying drawing, forming part thereof.

Fig. 1 is a top plan view, partly broken away, of a combined signal light and rear view mirror, showing my new design.

Fig. 2 is an end elevation, looking from the bottom in Fig. 1, and showing the full line portion thereof.

I claim:

The ornamental design for a combined signal light and rear view mirror, substantially as shown.

PAUL A. CHAMBERS.
